UNITED STATES PATENT OFFICE.

JOHN N. MURPHY, OF SAYLESVILLE, RHODE ISLAND.

SPRING FOR VEHICLES.

1,370,038.

Specification of Letters Patent.

Patented Mar. 1, 1921.

Application filed December 15, 1919. Serial No. 344,801.

To all whom it may concern:

Be it known that I, JOHN N. MURPHY, a citizen of the United States, residing at 20 Chapel street, Saylesville, in the county 5 of Providence and State of Rhode Island, have invented certain new and useful Improvements in Springs for Vehicles, of which the following is a specification.

My invention relates to springs for vehicles and the purpose of my invention is to provide a laminated spring which will not require to be perforated for bolts in order to retain the leaves in position, but which will have an enveloping clasp adapted to inclose the spring at or about its middle portion, which clasp is united to the spring leaves by welding in the manner hereinafter described.

My device is explained in the drawings 20 accompanying this petition, in which—

Figure 1 represents the blank for the enveloping clasp before its application to the spring.

Fig. 2, a sectional view of the clasp in 25 place upon the spring through the line $y-y$ of Fig. 4.

Fig. 3, a cross-section through the line $X-X$ of Fig. 2.

Fig. 4, a perspective of a portion of the 30 spring with the clasp in place.

The same letters refer to the same parts throughout the various drawings.

In Fig. 1 A is the blank, forming the clasp before being applied to the spring and 35 consists of a suitably sized and shaped strip of bar metal of a thickness in proportion to the strength of the spring to which it is to be applied. This blank A is perforated as shown at $c-c'$ with one or more rectangular openings beveled as shown at $b-b'$, the length of the rectangular openings $c-c'$ being the same as the combined thickness of the various leaves of the spring to which it is to be applied.

45 S represents the leaves of the spring throughout.

While I have shown two openings $c-c'$ in the drawing, I may use in some springs only one such opening, or I may use more than 50 two, the number depending on the character of the spring.

The clasp A is applied to the spring as shown in Figs. 2 and 4 by first bending the same over a suitable form and then sliding it over the end of the spring. When first applied to the spring, the extremities of the

clasp A will leave a space adjacent to their line of union, as shown at a , Fig. 4. The rectangular openings $c-c'$ are so beveled as to have their widest portion of the opening outward and narrowing inward as shown at b in Fig. 3.

When the clasp A has been placed upon its spring, it is clamped temporarily and the space at a , Fig. 4, and those formed by the rectangular opening $c-c'$ shown in the same figure are then filled in by the electric or other suitable welding process, the beveling of the openings $c-c'$ aiding in the application of the heat.

By the welding process the clasp A and the several leaves of the spring are firmly united so as to form practically a single body, the welded portion a giving additional strength.

By the use of the rectangular openings $c-c'$ the welding process is greatly facilitated and the union of the clasp with the spring leaves made much stronger.

In Figs. 2, 3 and 4 the clasp is shown 80 after the welding has taken place at one of the rectangular openings, the welding substance being represented by c'' and the welding material at the ends of the clasp being shown in Figs. 2 and 4 by a .

By my process, the spring is strengthened at the middle portion, whereas by the use of bolts or other perforations it is actually weakened. The clasp is cheap and readily constructed, the blanks A being readily 90 struck out of suitable bar metal and the application to the spring is quickly, easily, and inexpensively made.

The welding process expands the clasp slightly and as its union with the spring is 95 formed while the parts are hot, the subsequent cooling contracts the clasp and makes its grip on the leaves more secure.

I am aware that prior to my invention the welding process has been used for the 100 purpose of uniting spring leaves together, but I am not aware that the welding process has ever been used in connection with a clasp which completely envelops or encircles the spring leaves.

Having now described my invention, what I claim and desire to secure by Letters Patent is:—

1. In a vehicle leaf spring, a plurality of leaves, a clasp inclosing the leaves, said 110 clasp being formed of a strip having spaced slots therein extending longitudinally of the

strip, the ends of the clasp being spaced from each other and a welding material in one of said slots and between the ends of the clasp for uniting the clasp to the spring 5 leaves.

2. In a vehicle leaf spring, a plurality of leaves, a clasp inclosing the leaves, said clasp being formed of a strip having spaced slots therein extending longitudinally of the 10 strip with one slot opening at one end of the strip, the ends of the clasp being spaced from each other, and a welding material in the end slot and extending between the ends of the clasp for uniting the clasp to the 15 spring leaves.

3. In a vehicle leaf spring, a plurality of leaves, a clasp inclosing the leaves, said clasp being formed of a strip having spaced slots therein with the side walls thereof out- 20 wardly beveled and extending longitudi-

nally of the strip with one slot opening at one end of the strip, the ends of the clasp being spaced from each other, and a welding material in the end slot and extending between the ends of the clasp for uniting the 25 clasp to the spring leaves.

4. In a vehicle leaf spring, a plurality of leaves, and a clasp inclosing the leaves, and having portions thereof welded to the leaves.

5. In a vehicle leaf spring, a plurality of 30 leaves, a clasp inclosing the leaves, and having portions thereof cutaway, and welding material sealing the clasp to the leaves at the cutaway portions.

In testimony whereof I affix my signature 35 in presence of two witnesses.

JOHN N. MURPHY.
